UNITED STATES PATENT OFFICE.

LONGLEY LEWIS SAGENDORPH, OF PHILADELPHIA, PENNSYLVANIA.

DESIGN FOR METALLIC LATHING.

SPECIFICATION forming part of Design No. 19,721, dated March 25, 1890.

Application filed February 17, 1890. Serial No. 340,794. Term of patent 14 years.

To all whom it may concern:

Be it known that I, LONGLEY LEWIS SAGENDORPH, a citizen of the United States, residing at Philadelphia, in the county of Philadelphia, State of Pennsylvania, have invented and produced a new and original Design for Metallic Lathing, of which the following is a specification, reference being had to the accompanying drawing, forming a part thereof, which represents a portion of a metallic lathing-strip showing my design.

My design consists of a corrugated surface having the elongated openings A and circular openings B in alternate convex corrugations ²⁰ ₁₅ a and b, as shown. It is evident that the

length of the elongated openings A may be varied, as may also the distance apart of the circular openings B, without departing from the leading feature of my design.

What I claim is—

The design for metallic lathing herein shown and described, consisting of a corrugated surface having the elongated openings A and circular openings B in alternate convex corrugations, as set forth.

LONGLEY LEWIS SAGENDORPH.
